UNITED STATES PATENT OFFICE.

PHILIP A. BECKER, OF NEW YORK, N. Y.

SUPPLEMENTAL DISPLAY-CASE.

1,150,329.

Specification of Letters Patent.

Patented Aug. 17, 1915.

Application filed November 13, 1914. Serial No. 871,958.

To all whom it may concern:

Be it known that I, PHILIP A. BECKER, a citizen of the United States, and a resident of New York, borough of Brooklyn, county 5 of Kings, and State of New York, have invented certain new and useful Improvements in Supplemental Display-Cases, of which the following is a full, clear, and exact specification.

10 This invention relates more particularly to a class of display cases adapted to be used in conjunction with boxes.

My invention has for its object primarily to provide a supplemental display case designed to be detachably applied to a box whereby goods, such as cigars and other tobacco products, may be advantageously displayed for sale on a counter, show case, and the like without subjecting the goods to being damaged by air and dust as well as preventing the goods from being handled or tampered with, and which consists essentially of a transparent body preferably of substantially a triangular shape having an open bottom and an open back. This transparent triangular body is positioned on the open top of the body of a box provided with a lid hinged thereto so that its front plate will be disposed upwardly on an incline toward the lid of the box, and this front plate may be hinged to the body of the case to permit it to be swung to open or closed positions thereon, or the front plate may be fixed to the body.

35 Another object of the invention is to provide one or more catches to permit the transparent body to be removably fastened against accidental displacement to either the body of the box or to its lid; and a further 40 object of the invention is to provide on the top of the front plate of the body of the case a transverse plate adapted to serve for displaying a sign and also as a handle by which the hinged front plate may be swung.

45 With these and other objects in view, the invention will be hereinafter more particularly described with reference to the accompanying drawings which form a part of this specification in which similar characters of 50 reference indicate corresponding parts in all the views, and will then be pointed out in the claims at the end of the description.

In the drawings, Figure 1 is a perspective view showing a box with one form of supplemental display case embodying my invention applied thereto. Fig. 2 is a sectional

view taken through one of the upper corner portions of the case shown in Fig. 1, the front plate being closed on the body of the case. Fig. 3 is a perspective view showing 60 a modified form of the case applied to a box. Fig. 4 is a perspective view showing still a different form of the case applied to a box. Fig. 5 is a vertical section taken through the case and the box shown in Fig. 4, and Fig. 65 6 is a perspective view illustrating the case and the box shown in Fig. 4 when the case is swung open from the body of the box.

The supplemental display case has a transparent body 10 composed of two approximately triangular end walls, or plates 11 and 12 which may be of glass or other transparent material, and these end plates are inclosed in frames, as 13 and 14, made preferably of wire of substantially the same width 75 as the thickness of the glass, the end plates being held in their frames by a number of clips, as 15. The lower front corners of the triangular frames 13 and 14 are connected by a transverse wire rod 16, and the lower 80 rear corners of these frames are connected by a transverse wire rod 17, while the upper corners of the frames are connected by a cross-bar 18. The cross-bar 18 is of a width so as to overhang the rear edges of the end 85 plates or walls of the body of the case, and the free lengthwise edge of this bar is slightly curved downwardly to provide a groove 19 thereunder. Pivoted by one or more hinges, as 20 and 21, to the cross-bar 90 18 is a second transverse bar 22 which may be substantially U-shaped as viewed transversely whereby a groove 23 is formed therein, and in this groove is disposed the upper edge of a front plate 24 of glass or other 95 transparent material. The side and front edges of the transparent plate 24 are inclosed in a wire frame 25 connected thereto by clips similar to the clips 15, and this plate together with its frame are of dimensions so 100 as to close in entirety the front opening between the triangular end plates of the display case when closed thereupon. The transparent body of the case is made so that the lower edge of its hinged front plate and 105 the lower edges of its end walls are on the same relative plane, and this body is made of a size corresponding to the width and length of the box, as 26, so as to rest upon the upper edges of the walls of the box, as 110 shown, and the body of the case is of a height equivalent to approximately the

width of the lid 27 of the box. When the display case is applied to the box so that its transparent triangular body 10 is positioned on the open top of the body of the box the 5 lid of the box is moved upwardly and guided into the groove 19 under the overhanging part of the cross-bar 18. The lid of the box will then be held to close the open back of the body 10 of the case, and in order to retain the body 10 to the body of the box, on the transverse wire rod 16 is provided a catch, as 28. The catch 28 may be of any suitable type, though I prefer to employ the form, as illustrated, which has a straddle 10 bar 29 depending from the wire rod 16. This straddle bar is guided over the upper edge of the front wall of the body of the box, and through a threaded hole in one arm of the straddle bar is passed a set screw 30 15 adapted when revolved to engage the front wall of the body of the box. The transparent body 10 of the display case will thereby be held on the box against accidental movement, and to permit the transparent plate 24 to be conveniently swung on its 20 hinges to open and closed positions on the body of the display case as well as on the body of the box, on top of the U-shaped transverse bar 22 is fixed a strip or handle 25 31 which extends rearwardly of the body of the case and the lid of the box. By directing this strip 31 in downwardly or upwardly directions the transparent plate 24 will be 30 swung accordingly to and from the body of the case to permit the contents of the box 35 to be dispensed through the front of the case, and by making this strip of a desired length and width a suitable sign, as 32, may be inscribed thereon.

40 In Fig. 3 is shown a form of the supplemental display case adapted to permit the contents of the box to be dispensed through the open back of the case. This form of the display case has an approximately triangular body 33 composed of spaced triangular end walls or plates 34, 35 and an inclined front plate 36, all of which are of glass, or other transparent material, and these parts are connected together by being 45 inclosed in a frame 37 made preferably of wire rods of a size similar to the thickness of the transparent plates, the plates being secured in the frame by a number of clips 38 which may be similar to the clips 15. 50 The transparent front plate 36 is thereby held stationary to the transparent end plates 34 and 35 instead of being hinged thereto, and this form of the case has an open bottom and an open back. Connecting the lower rear corners of the frame of the end plates 34 and 35 is a rod 39, and connecting the upper corners of these end plates is a transverse bar 40. The lower part of the transparent body 33 of the case 55 is of a length and width corresponding to

the length and width of the body of the box, as 41, having a lid 42 to which it is applied so that the case will rest on the upper edges of the walls of the box body to allow access into the box through the open back of the 70 body of the case, and the body of the case is held against accidental displacement to the box by a number of catches, as 43. Both of the catches 43 are similar in formation to the catch 28, shown in Fig. 1, and these 75 catches extend from the lower edges of the end plates 34 and 35 for being guided over the upper edges of the end walls of the body of the box to which they are detachably fastened by means of set screws 44. As 80 illustrated, when the case is applied to the box in this manner its open back will be above the rear of the box so that the lid may be swung to open and close the back of the case. The extreme height of the body of 85 the case is preferably similar to the width of the lid of the box, and when the box lid is closed on the case it is detachably held in position by a catch, or clip, as 45, which may be in the form of a spring hook extending rearwardly from the transverse bar 40 so as to yieldingly engage the upper edge of the lid as well as permitting the lid to be easily released therefrom under slight pressure for permitting the contents of the box 90 to be dispensed through the open back of the body of the case.

Figs. 4, 5, 6 illustrate views of a form of the supplemental display case adapted to be applied to the lid of a box so that the case 100 in entirety may be swung to open and closed positions on the body of the box by swinging the lid accordingly. This type of the display case has an approximately triangular body 46 consisting of end walls, or plates 47, 48 and an inclined front plate 49, all of which may be of glass, or other transparent material inclosed in a frame, as 50, connected to the plates by clips 51, and these parts are similarly constructed to the body 105 33 of the display case, shown in Fig. 3, the lower rear corners of the frame of the end plates being connected by a rod 52 and the upper corners of the frame of these end plates being connected by a transverse bar 110 53. The body 46 of this case also has an open back and an open bottom, and this body is of a size corresponding to the dimensions of the body of a box, as 54, so as to be adapted to rest on the upper edges of 115 its walls, while the back of the body 46 is of a size approximately similar to the dimensions of the lid 55 of the box. When this case is applied to the box the body 46 is placed on the lid so that its open back will be closed by the lid and so that the open bottom of the case will be in opposed relation to the interior of the box. The body of the display case is then held firmly to the lid 120 of the box by two catches 56 which are simi- 125 130

lar to the catches 28 and 43 of the other forms of the case, and each of the catches 56 is secured at the lower ends of the respective frames of the end plates 47 and 48 in a manner so as to be removably disposed over the opposed side edges of the lid of the box, and each of the catches 56 has a set screw 57 which is rotatably guided into releasable engagement with the lid. To also hold the top of the lid to the body 46 of the case, on the transverse bar 53 is a strip, as 58, which may be of a width and length to permit a suitable sign, as 59, to be inscribed thereon. The strip 58 is of a width to extend 10 rearwardly of the body, and the projecting edge of the strip is curved downwardly, as at 60, for the top edge of the lid of the box to be disposed thereunder previous to being fastened to the catches 56. When it is desired to dispense goods from this box the display case will be swung to an open position from the top of the body of the box by moving the strip 58 and the box lid backwardly, and when the strip and the lid are reversely directed the case will be closed upon the open top of the box. Thus by the use of these forms of supplemental display cases goods in boxes may be advantageously displayed for sale on counters, show cases, and the like without subjecting the goods to being damaged by air and dust as well as preventing the goods from being handled or tampered with.

In the foregoing description, I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope of the appended claims.

Having thus described my invention, I claim as new and desire to secure by Letters Patent:—

1. A supplemental display case of the character described, comprising a transparent body having an open bottom, an open front, and an open back, adapted to be disposed on the body of a box having a lid hinged thereto so that the open bottom of the transparent body will rest on the top of the walls of the box and so that the open back may be closed by the lid of the box, means on the transparent body for detachably connecting it to the box and its lid, and a transparent front plate hinged to the body of the display case, adapted to be swung to open and closed positions on the open top of the body of the box.

2. A supplemental display case of the character described, comprising a substantially triangular transparent body having an open bottom, an open front, and an open

back adapted to be disposed on the body of a box having a lid hinged thereto so that the open bottom of the triangular body will rest on the top of the walls of the box and so that the open back may be closed by the lid of the box, catches on the triangular body for detachably connecting it to the box and its lid, and a transparent front plate hinged to the triangular body, adapted to be swung to open and closed positions on the open top of the body of the box.

3. A supplemental display case of the character described, comprising a body having two spaced end walls connected together to provide an open bottom, an open front, and an open back, adapted to be disposed on the body of a box having a lid hinged thereto so that the open bottom of the body of the case will rest on the top of the walls of the box and so that the open back may be closed by the lid of the box, means on the body of the case for detachably connecting it to the box and its lid, and a transparent front plate hinged to the body of the case for being swung to open and closed positions on its open front.

4. A supplemental display case of the character described, comprising a body having two spaced transparent end walls connected together to provide an open bottom, an open front, and an open back, adapted to be disposed on the body of a box having a lid hinged thereto so that the open bottom of the body of the case will rest on the top of the walls of the box and so that the open back may be closed by the lid of the box, catches on the body of the case for detachably connecting it to the box and its lid, and a transparent front plate hinged to the body of the case for being swung to open and closed positions on its open front.

5. A supplemental display case of the character described, comprising a body having two spaced substantially triangular transparent end plates inclosed in a frame to provide an open bottom, an open front, and an open back, adapted to be disposed on the body of a box having a lid hinged thereto so that the open bottom of the body of the case will rest on the top of the walls of the box, catches on the body of the case for detachably connecting it to the box and its lid, a transparent front plate hinged to the frame of the body of the case for being swung to open and closed positions on its open front, and means on the front plate to permit it to be swung to and fro as well as permitting a sign to be displayed thereon.

6. A supplemental display case of the character described, comprising a transparent body having an open bottom and an open back, adapted to be disposed on the body of a box having a lid hinged thereto so that the open bottom of the transparent body will rest on the top of the walls of the box and

so that the open back may be closed by the lid of the box, and means on the transparent body for detachably connecting it to the box and its lid, substantially as set forth.

7. A supplemental display case of the character described, comprising a transparent body having an open bottom and an open back, adapted to be disposed on the body of a box having a lid hinged thereto so that the open bottom of the transparent body will rest on the top of the walls of the box and so that the open back may be closed by the lid of the box, and catches on the transparent body for detachably connecting it to the box and its lid, substantially as set forth and for the purpose specified.

8. A supplemental display case of the character described, comprising an approximately triangular transparent body having an open bottom and an open back, adapted to be disposed on the body of a box having a lid hinged thereto so that the open bottom of the transparent body will rest on the top of the walls of the box and so that the open back may be closed by the lid of the box,

and catches on the transparent body for detachably connecting it to the box and its lid, substantially as set forth and for the purpose specified.

9. A supplemental display case of the character described, comprising an approximately triangular body having two spaced transparent end plates and a transparent front plate to provide an open bottom and an open back, adapted to be disposed on the body of a box having a lid hinged thereto so that the open bottom of the triangular body will rest on the top of the walls of the box and so that the open back may be closed by the lid of the box, and means on the triangular body for detachably connecting it to the box and its lid, substantially as set forth and for the purpose specified.

This specification signed and witnessed this twelfth day of November A. D. 1914. 45

PHILIP A. BECKER.
